UNITED STATES PATENT OFFICE.

GEORGE H. EVANS, OF OROVILLE, CALIFORNIA, ASSIGNOR TO THE RISDON IRON AND LOCOMOTIVE WORKS, OF SAN FRANCISCO, CALIFORNIA.

DESIGN FOR A THROAT FOR HYDRAULIC ELEVATORS.

SPECIFICATION forming part of Design No. 32,500, dated April 10, 1900.

Application filed March 14, 1900. Serial No. 8,674. Term of patent 14 years.

To all whom it may concern:

Be it known that I, GEORGE H. EVANS, a subject of the Queen of Great Britain, residing at Oroville, county of Butte, State of California, have invented and produced a new and original Design for a Throat for Hydraulic Elevators, of which the following is a specification, reference being had to the accompanying sheet of drawings, forming a part thereof, wherein—

Figure 1 is a perspective view of the throat, and Fig. 2 is a vertical sectional view taken on line $\alpha\alpha$ of Fig. 1.

As shown in the drawings, the leading or material feature of my design consists of the tubular body portion A, having a central circular flanged portion A' and an upper end circular flanged portion A². The inner wall of the tubular body portion is inwardly inclined

from its upper edge to point 3, and from said point 3 the inner wall is outwardly inclined to the lower edge thereof, Fig. 2 of the drawings. A sectional portion of the lower edge of the tubular body is removed, as indicated by reference-letter *a*, Fig. 1 of the drawings. 20 25

Having thus described my invention, what I claim as new, and desire to secure by Letters Patent, is—

The design for a throat for hydraulic elevators, as herein shown and described. 30

In testimony whereof I affix my signature, in the presence of two witnesses, this 19th day of January, 1900.

GEORGE H. EVANS.

In presence of—

N. A. ACKER,
D. B. RICHARDS.
